UNITED STATES PATENT OFFICE.

CARL MUEHLEISEN, OF BERLIN, GERMANY, ASSIGNOR TO MERGENTHALER LINOTYPE COMPANY, OF BROOKLYN, NEW YORK, A CORPORATION OF NEW YORK.

SLUG-EJECTING MECHANISM FOR MATRIX COMPOSING AND LINE-CASTING MACHINES.

Application filed May 22, 1925, Serial No. 31,988, and in Germany May 31, 1924.

In matrix composing and line casting machines, especially those having a mould wheel adapted to carry a plurality of moulds simultaneously, it is already known for removable 5 ejector blades to be provided so that when changing over from one measure or body to another, the ejector blade may also be quickly changed. For this purpose it has already been proposed to arrange edgewise one above 10 the other a plurality of narrow ejector blades, each having the width of a typographical unit or a multiple thereof, and to connect with the ejector driving mechanism, a number of these blades which in 15 width will collectively correspond with the length of the respective lines or slugs. It has also been proposed to store in a receptacle a plurality of juxtaposed ejector blades, those corresponding to the desired 20 width being brought into operative position through lateral displacement.

Both the aforesaid constructional forms have the disadvantage that the ejector blades can only be so selected that the thinnest will 25 correspond to the slug of smallest body dimension which will be used, usually six point, and that also the width of the ejector blades can only approximate to the actual length 30 of the slugs. As the thickest slugs are also ejected by these thin ejector blades considerable trouble arises through their becoming embedded into the feet of the slugs and the latter sticking in the moulds instead of being ejected.

The present invention overcomes this difficulty by the fact that the machine is equipped 35 with a removable ejector blade magazine which contains a number of ejector blades corresponding with the moulds present on the mould wheel. The ejector blades themselves 40 are also removable from the magazine. It is thus possible to store in this magazine, such blades as actually correspond with the moulds for the time-being on the mould wheel, i. e. 45 ejectors which will accurately fit each of the respective moulds and which may easily be substituted one for another. If the mould itself is altered or the moulds exchanged for others, the ejector blade magazine is simultaneously taken out and a corresponding

alteration of the respective ejector blades is effected.

The drawings illustrate by way of example a constructional form of the present inventive idea and in these drawings:— 55

Figure 1 is a diagrammatic illustration of the ejecting mechanism of a matrix composing and line casting machine;

Figure 2 is a horizontal section through Figure 1; 60

Figure 3 is an elevation of the top part of Figure 1 as seen from the left-hand side;

Figure 4 is a vertical section on the line 4—4 of Figure 1;

Figure 5 is an enlarged view of the top 65 left-hand portion of Figure 1;

Figure 6 is a plan of Figure 5 with the control lever omitted;

Figure 7 is an elevation of the ejector blade magazine detached; 70

Figure 8 is a plan thereof;

Figure 9 is a face view of a single ejector blade, and

Figure 10 is a plan of Figure 9 illustrating two ejector blades of different thicknesses. 75

In the drawing *a* is the ejector blade magazine containing the different ejector blades *b* (in the present constructional form four of these blades are provided to correspond with a mould wheel having four 80 moulds). The magazine *a* can be moved laterally in a manner similar to that adopted in existing constructional forms, i. e. forward and backward relatively to the plane of representation in Figure 1, so as to bring any 85 requisite ejector blade *b* into the operative position in which it will be coupled with the ejector *c*. This ejector *c* consists of a blade similar to the blades *b*. The coupling may be conveniently effected through a T-shaped recess *b*¹ in the ejector blade *b*, and a T-shaped projection or head *c*¹ on the ejector *c* (see Figure 9). The ejector blades *b* are inserted into the magazine *a* from the front. In order to provide guides for the 90 blades *b* in the magazine *a*, the top wall of said magazine (Figures 7 and 8) is provided near the front with recesses within which filling strips or plates *e* are capable of being turned about a common pivot *e*¹. 100

In their operative position, the filling plates *e* engage above and below with recesses *d*; they may, however, be rocked upwardly about the pivot *e*¹ into the position shown in dotted lines in Figure 7. As the individual ejector blades *b*, as shown particularly in Figure 10, are thicker at their rear ends, and, at those parts are of the same thickness as the ejector *c*, they can only be inserted into the magazine after the filling plates *e* have been raised into the dotted-line position shown in Figure 7. After the insertion of the ejector blades whose rear extremities completely fill the width of the magazine, the filling blades *e* are turned down between or beside the respective ejector blades, as is shown in Figure 10, in respect of two of such blades. The body size of each filling plate *e* together with the body size of the respective blade *b* is uniform, and equals the corresponding dimension of the rear end of the ejector blade. Consequently, if a change of ejector from one body size to another is made, it is also necessary to change the respective filling plate or plates *e*, which can easily be effected after removing the pivot pin *e*¹.

For all practical purposes it is sufficient to have two different thicknesses of ejector blades, viz:—thin ones for the smaller bodies and thicker ones for the larger bodies. When ejector blades wider than the ejector *c* are required they are provided, as shown in Figure 9, with upstanding projections *b*²

at the front. The whole magazine with the ejector blades is inserted into the so-called mould wheel slide *f* in the manner shown in Figures 1, 2, 5 and 6. The mould wheel slide, as is already known, is that portion of the machine which carries the pivot *f*¹ about which revolves the mould wheel *f*² carrying the moulds *f*³.

In order to insert the magazine *a* into the mould wheel slide *f*, the latter is provided with guides *f*⁴ adapted to receive a corresponding number of projections on the magazine, and, in addition to this, the magazine itself is provided with a handle *g* for facilitating its removal and replacement. The mould wheel slide *f* is slightly cut away in front at the top in order to permit the removal of a magazine containing ejector blades *b* having the before-described projections *b*².

When it is desired to effect a change of ejector blade magazine, the so-called vise frame is lowered frontwise, so as to give access to the mould wheel slide *f*, which must then be pulled forward until its rear edge passes beyond the front of the machine frame when the said magazine is free to be removed from the machine.

The before-mentioned guides *f*⁴ are, as shown in Figures 2 and 6, obliquely inclined

so that longitudinal displacement of the magazine will simultaneously cause the latter to be moved laterally. This lateral movement serves to bring the ejector blades *b* stored in the magazine successively into and out of engagement with the ejector *c*. 65

For the purpose of moving the magazine longitudinally, the latter is provided with a projecting stud *h* adapted to be engaged by the forked rear extremity of a link *k* whose other end is attached to one arm of a hand lever *i*. The forked end of the link *k* permits of easy disconnection from the stud *h*, by lifting said link into a position such as that shown in dotted lines in Figure 5, when such disconnection is required as a preliminary to effecting a change of magazine. In order to retain the link *k* in operative engagement with the stud *h*, as shown, it is provided with a laterally extending pin *n*, and the mould wheel slide *f* is provided with a cover plate or latch *m* which can be turned about a pivot *m*¹ fast to said slide, the said cover plate being adapted to overlie the pin *n* and thereby prevent the link *k* from accidentally leaving 80 its operative position although the pin *n* is free to travel beneath the cover plate *m* in the longitudinal direction. In order to retain the cover plate *m* in the locking position, a spring-pressed pin *m*² Figure 5, is 85 provided, which engages with a corresponding recess in the underside of the said cover plate *m*. 90

The before mentioned hand lever *i* is bifurcated at its lower end, and is pivotally mounted in a block or bracket *o*¹ by means of a pivot *i*¹. The upper end of this lever is provided with a handle whilst the lower end is pivotally connected with the link *k* previously mentioned. The block *o*¹ is attached to a bar *o* which, at one end extends over the vise *p*, whilst its other end behind the vise is rigidly connected to the mould wheel slide *f*. The upper portion of the lever *i* moves in registering relationship to a segmental scale *q* (Figure 3), which is conveniently provided with holes with which a spring-controlled pin on the lever *i* engages, when an ejector blade is in its different operative positions. The scale is supported by a guide or bracket *r* provided on the front plate of the machine. 100

The ejector *c* is rigidly attached to the so-called ejector slide *s*, which is connected in the known manner with the ejector lever *t* by means of a connecting rod *u*. The connection between the rod *u* and lever *t* is effected through a guide member *v* pivoted to the said lever, and in which the rod *u* is longitudinally slidable. A spring *w* connects the rod *u* with the guide member *v* and pulls the ejector slide *s* back until the rear end of the latter contacts with a stop *x*. 110

fixed to the mould wheel slide f . In this position the T-shaped recesses b^1 of the ejector blades b are all in registering alignment with the T-shaped head c^1 .

5 The spring w also serves to take up any excess motion of the ejector lever t and also makes it possible for the mould wheel slide to first get into casting position.

The forward movement of the ejector lever t is effected in known manner by a cam member engaging one extremity of said lever, whilst the return movement is effected through a roller z on the lever t , being engaged by a cam z^1 .

15 The mode of operation of the device is as follows:—when a line has been cast in the usual manner, the mould wheel f^3 rotates until the mould slot is in front of the ejector, then, through the action of the connecting rod u , the ejector slide s , and ejector c and the selected ejector blade b all move forward together to eject the slug from the mould. When a change of mould is effected, the lever i must be correspondingly rocked 25 to move the ejector blade magazine a in a lateral direction, and thereby disconnect from the ejector c , the blade last previously engaged with it, and engage with said ejector the particular blade appropriate to the 30 newly selected mould.

When the moulds on the mould wheel are actually changed for others of different measure or body, the whole magazine a with the ejector blades b is removed and other 35 blades of the appropriate dimensions are substituted for those last previously used, the filling plates e being also changed if rendered necessary by such substitution of ejector blades.

40 It is to be understood that the details of the present constructional form may be varied, as the essential feature of the present invention resides particularly in the fact that the ejector blades are stored in a special 45 magazine which may be changed as a whole.

Having described my invention, I declare that what I claim and desire to secure by Letters Patent is:—

1. A slug ejecting mechanism for line 50 casting machines comprising a suitable support, a set of interchangeable magazines containing different sized ejector blades, interconnecting means for the magazines and the support whereby any selected blade 55 magazine may be readily applied to and removed from the support, means for adjusting the selected magazine to bring one or another of its contained blades into operative position and releasable connections between said adjusting means and the magazine in use; whereby the magazine in use 60 may be removed and replaced by another magazine containing different sized blades.

2. Ejecting mechanism according to claim 65 1 characterized by the fact that the ejector

blades may be removed from the magazine individually and independently of each other and may be replaced by others.

3. Ejecting mechanism according to claim 1 characterized by the fact that all the ejector blades at their rear edges where they engage with the ejector, are of the same thickness, preferably that of the ejector, whilst the remaining portion adapted to enter the mould substantially corresponds in thickness with the body dimension of the slug, and characterized further by guides of different thickness being intercalated between individual ejector blades in the front part of the magazine, the body dimension of the front portions of these blades added to the respective thickness of the respective guides corresponding with the thickness of the rear edges of the said blades.

4. Ejecting mechanism according to claim 1 characterized by the fact that the front part of the blade magazine behind the mould is provided with interchangeable intermediate partitions e adapted to guide the ejector blades.

5. Ejecting mechanism according to claim 1 characterized by the fact that the intermediate partitions e are movably or pivotably engaged with recesses in the top and bottom walls of the magazine, so as to enable them to be swung away from the front part of the magazine for enabling the blades to be removed and substituted by others.

6. Ejecting mechanism according to claim 1, characterized by the fact that the ejector blade magazine is mounted in the mould wheel slide and the latter is recessed or cut away at the side to permit the free removal of the magazine therefrom in a lateral direction.

7. Ejecting mechanism according to claim 1 characterized by the fact that the operative connection between the magazine shifting lever i and the ejector blade magazine a is easily broken, as by means of a pin h and a fork engaging said pin.

8. Ejecting mechanism according to claim 1 characterized by a locking device (m , n) adapted to hold the magazine shifting rod in operative connection with the magazine.

9. Ejecting mechanism according to claim 1 characterized by the fact that the magazine shifting lever i is mounted upon a bar o connected to the mould wheel slide and extending over the vise.

10. Ejecting mechanism according to claim 1 characterized by the fact that a spring-controlled connecting rod is inserted in the ejector operating mechanism, to compensate for excess motion of said operating mechanism when the ejector slide s is arrested in its rearmost position, as by a stop x .

11. In ejecting mechanism such as described, the combination with a mould wheel slide and an ejector slidable therein, and a

plurality of ejector blades adapted to be moved laterally to engage the ejector one at a time, of an ejector blade magazine longitudinally adjustable in the mould wheel slide, means adapted to move the magazine laterally simultaneously with its longitudinal movement, actuating devices adapted to impart the said longitudinal movement to the magazine, a forked link operatively connected to the actuating devices, and a stud on the magazine releasably engaged by the fork of the link in all lateral positions of the magazine.

12. In ejecting mechanism such as described, the combination with a mould wheel slide and an ejector slidably therein, and a plurality of ejector blades adapted to be moved laterally to engage the ejector one at a time, of an ejector blade magazine longitudinally adjustable in the mould wheel slide, means adapted to move the magazine laterally simultaneously with its longitudinal movement, actuating devices adapted to impart the said longitudinal movement to the magazine, a forked link operatively connected to the actuating devices, a stud on the magazine releasably engaged by the

fork of the link in all lateral positions of the magazine, and means adapted to maintain connection between the fork and stud, adjustable to permit of disconnection of said fork and stud.

13. In ejecting mechanism such as described, the combination with a mould, a mould wheel carrying same, a mould wheel slide rotatably supporting the mould wheel, an ejector slidable in the mould wheel slide, and a plurality of ejector blades adapted to be moved laterally to bring any selected ejector blade into registering alignment with the mould and ejector, of an ejector blade magazine longitudinally adjustable in the mould wheel slide, means adapted to move the magazine laterally simultaneously with its longitudinal movement, actuating devices operatively connected to the magazine adapted to impart said longitudinal movement to the magazine, and means adapted to maintain the said operative connection, adjustable to permit of this said connection being broken.

In testimony whereof I have affixed my signature hereunto.

CARL MUEHLEISEN.
